CLAIM

The ornamental design for a shoulder rest for violin or like instrument, as shown and described.

DESCRIPTION

FIG. 1 is a perspective view of a shoulder rest for violin or like instrument showing my new design;

FIG. 2 is top plan partially perspective view of the same shoulder rest when in place on a violin;

FIG. 3 is a side view of the same shoulder rest when in place on a violin;

FIG. 4 is an enlarged bottom plan view of the same shoulder rest;

FIG. 5 is an enlarged side view of the same shoulder rest as seen in FIG. 3;

FIG. 6 is a cross-sectional view on lines 6—6 of FIG. 5;

FIG. 7 is a cross-sectional view on lines 7—7 of FIG. 5; and, FIG. 8 is a enlarged fragmentary view of an end clamping portion of the same shoulder rest.

The broken line showing of a violin in FIGS. 2 and 3 is for illustrative purposes only and forms no part of the design.
